UNITED STATES PATENT OFFICE.

GEORGE F. GAVARD, OF LOS ANGELES, CALIFORNIA.

TIME SWITCH.

Application filed November 16, 1923. Serial No. 675,088.

To all whom it may concern:

Be it known that I, GEORGE F. GAVARD, a citizen of the United States, residing at Los Angeles, in the county of Los Angeles and State of California, have invented new and useful Improvements in Time Switches, of which the following is a specification.

This invention relates to time switches, and has for an object to provide a simple, 10 practicable and reliable time mechanism for automatically closing and breaking, and for maintaining closed for a variable period of time, an electric circuit, such, for instance, as the circuit of an advertising illuminated sign.

Another object is to provide, in combination, a twenty-four hour clock dial and means adjustable to be registered with hours of the dial to determine the time of closing 20 and the time of breaking an electric circuit.

Other objects and advantages will be made manifest in the following specification of an embodiment of the invention illustrated in the accompanying drawings, 25 wherein:

Fig. 1 is a front elevation of the improved device.

Fig. 2 is a section on line 2—2 of Fig. 1.

Fig. 3 is a section on line 3—3 of Fig. 1.

Fig. 4 is a front elevation of the parts with the dial plate removed.

Fig. 5 is a front elevation with the hour hand pointer removed.

The invention consists of a suitable box 35 or shell 2 having a front plate 3 provided with any suitable dial device 4 which, in the present case is shown as divided in 24-hour circle, a 12-hour zone of the digits being indicated in light characters 4^a and the remaining 12 digits being indicated in contrasting shade or color as indicated at 4^b. Centrally of the dial there is provided a setting-knob 5 on the hour arbor of a clockwork C, the setting-knob being attached to an hour-pointer 6 operating through one circle in 24 hours.

Secured to the hour shaft C of the clock work is a disc 7 which is provided with an inwardly deflecting yieldable finger 8, the finger and the disc constituting an electric conductor, the finger being engageable with relatively adjustable contact plates 10 and 11 of segmental form and which are rotatably mounted on a bearing 12, Fig. 2, through which the hour arbor C extends without contact. The bearing 12 is mount-

ed on an intermediate plate 13 which may be of insulating material, as also may be the front plate 3.

The contact segments 10 and 11 are in electric engagement and are each independently adjustable around the bearing 12 and are constantly in contact with a circuit track 14 having a circular part concentric with the bearing 12. To facilitate adjustment of the contact segments 10 and 11, these are each provided with outwardly projecting finger-pieces 15, movable in a concentric slot 16, in the front plate 3. The slot is of any suitable length and to adjust the contact segments it is only necessary to engage the projecting ends of the finger 15 and by these swing the contact segments 10 and 11 to any desired position on and around the track 14, Fig. 5.

The contacts 10 and 11 are relatively adjustable so as to provide for variation of effective track area to be engaged by the contact shoe 8 which is designed to engage portions of the contacts 10 and 11 while the

shoe 8 is being driven by the clock mechanism. The contact segment 10 is slotted at 10' to provide for a close adjustment of the segments one on top of the other. When in such relation the finger 15 of the segment 11 extends into the slot 10' of the segment 10. The contact shoe 8 sweeps in a circle within the position of the adjusting finger 15.

In use of the device, a circuit conductor 20 is attached to a terminal of a contact arm 21, disposed between the plates 3 and 13 and constantly engaging the conductor disc 7, as seen in Fig. 2. A circuit wire 21' is connected to the terminal of an end 14' of the track 14. A circuit may be closed when the contact shoe 8 rides upon the contact segments 10—11; the wires 20—21' obviously being extended and included in any suitable circuit which may, for instance, include an electric light L, a source of current B. The return circuit line 22 is shown as for convenience attached to a ground bar 23, which may be mounted on the shell or housing, as shown.

By providing a 24-hour dial and hour arbor mechanism, it will be seen that the contact shoe will make but one circuit in 24 hours, and therefore when the apparatus is used for controlling a night signal or advertising device including an electric light system, then when the adjustable segments

are set in the second or P. M. series of hour digits, the circuit will be closed only once during the 24 hours of a day.

Further embodiments, modifications and variations may be resorted to within the spirit of the invention.

What is claimed is:

1. In a time switch a twenty-four hour clockwork, a setting-knob mounted on the hour arbor of the clockwork, an hour pointer extending from the setting-knob, a disc mounted to rotate with the hour arbor, a brush extending from the disc, a bearing fixed concentric to the hour arbor, segmental contact plates mounted upon the bearing and adapted to slidably overlap to be adjustable in effective length, and the brush engaging the contact plates, a circuit track in constant contact with the contact plates, and finger pieces projecting outwardly from the

wardly from the contact plates for adjusting the plates.

2. In a time switch a twenty-four hour clockwork, a setting-knob mounted on the hour arbor of the clockwork, an hour pointer extending from the setting-knob, a disc mounted to rotate with the hour arbor, a brush extending from the disc, a bearing fixed concentric to the hour arbor, segmental contact plates mounted upon the bearing and adapted to slidably overlap to be adjustable in effective length and the brush engaging the contact plates, a circuit track in constant contact with the contact plates, finger pieces projecting outwardly from the
